(57) **CLAIM**

The ornamental design for a combined positive displacement pump with motor, as shown and described.

DESCRIPTION

FIG. 1 is a front elevational view of a combined positive displacement pump with motor showing my new design;

FIG. 2 is a left side elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is a diagonal front perspective view seen from left side thereof;

FIG. 8 is a diagonal front perspective view seen from right side thereof;

FIG. 9 is a diagonal rear perspective view seen from right side thereof; and,

FIG. 10 is a diagonal rear perspective view seen from left side therefor.
